1 Claim. (Cl. 219—364)

ABSTRACT OF THE DISCLOSURE

Apparatus for heating compressible fluids used to bulk yarn by passing the fluid through a plurality of passageways in a heat exchanger. A continuously energized base load heater is located at one side of each of the passageways. An intermittently energized swing load heater is located at the other side of each of the passageways. The operation of the swing load heaters is controlled by control means responsive to the temperature of the heat exchanger. The end position swing load and base load heaters on the heat exchanger are energized at a higher voltage than the intermediate position swing load and base load heaters to compensate for heat losses at the ends of the heat exchanger.

This invention relates to an apparatus for heating compressible fluids used in the production of bulked yarns, the yarns being produced by feeding a yarn composed of a plasticizable polymer through a heated turbulent stream of fluid.

As described in British Patent Nos. 905,895 and 941,931, the temperature of the compressible fluid is critical to the bulking process and must be closely regulated since there is a correlation between bulking position temperature and yarn dyeability. Also, it has been discovered that heat losses occur at the end positions of the heat exchangers which results in undesirable dye variations of the bulked yarn heated by the end positions as opposed to the intermediate positions.

Accordingly, an object of this invention is to provide an improved apparatus for heating compressible fluid used in the production of bulked yarns. Another object is to provide an improved apparatus to compensate for heat losses at the end positions of the heat exchanger thus improving yarn dye uniformity. Other objects will appear hereinafter.

The objects of this invention are accomplished by an apparatus for heating compressible fluid used to bulk yarns which comprises, in general, a heat exchanger having a plurality of separate, co-planar passageways therethrough, means to supply compressible fluids to the passageways, a swing load heater on one side and a base load heater on the other side of each of the passageways, voltage source means connected to each intermediate heater, first switch means connected between the voltage source means and the intermediate swing load heaters, transforming means connected to the voltage source means to supply both the end position swing load and base load heaters with a predetermined voltage greater in magnitude than the voltage supplied by the voltage source means, second switch means connected between the transforming means and the end position swing load heaters, measuring means responsive to the temperature of the heat exchanger and control means responsive to the output of the measuring means to close the first and second switch means when the output of the measuring means falls below a predetermined point and to open the switch means when the output exceeds the predetermined point.

The embodiments of this invention and their advan-

2

tages can be more readily understood by referring to the accompanying drawings.

FIGURE 1 is a schematic diagram showing an embodiment of the invention.

FIGURE 2 is a schematic diagram showing the relationship between a yarn bulking jet and the heat exchanger.

FIGURE 3 is a block diagram showing the use of the heat exchangers with a recorder controller.

Referring to FIGURE 1, there is shown heat exchanger 10 having separate, co-planar passageways 12, 14, 16, 18, 20 and 22 therethrough. Manifold 24 is connected to the aforementioned passageways on one side of heat exchanger 10 and a source of compressed air (not shown) under a predetermined pressure is supplied to manifold 24 in the form of a stream of high velocity air 26. Electric cartridge heaters 28, 30, 32, 34, 36, 38, 40, 42, 44, 46, 48 and 50 are contained in heat exchanger 10 and arranged so that one heater is adjacent to each side of a passageway and in line with the axis of the passageway. Intermediate heaters 32, 36, 42 and 46 (termed base load heaters) are connected directly to line voltage 52 and are energized at all times when the power is on. For example, intermediate heater 32 is connected to lead 68 with lead 68 tied to the line voltage 52 by means of lead 77. For the sake of simplicity the heater circuit return paths to line voltage 54 are not shown in FIGURE 1. However FIGURE 2, which shows the return path to line voltage 54 for heaters 28 and 30, is illustrative of the return path for all the heaters. The remaining intermediate heaters 34, 38, 40 and 44 (termed swing load heaters) are also connected to line voltage 52 through conventional relay contacts C2; for example, heater 34 is connected to lead 70 with lead 70 connected to voltage source 52 through lead 76 and relay contacts C2. A variable transformer 56 is connected across line voltage 52 and 54. End position heaters 28 and 50 (termed base load heaters) are connected directly to adjustable lead 58, on transformer 56, through leads 79, 60 and 62. End position heaters 30 and 48 (termed swing load heaters) are connected to lead 58 through leads 64, 66, 78 and relay contacts C1. A thermocouple 74 is connected to heat exchanger 10 and conventional recorder controller 72. A precision variable resistor 80 is connected between recorder controller 72 and thermocouple 74.

FIGURE 2 illustrates the use of the novel apparatus of this invention to bulk yarn. As can be seen, only an exemplary part of heat exchanger 10 is illustrated. Yarn theradline 84 is passed through a jet 82. The jet is connected to passageway 12 in heat exchanger 10. A source of compressed air 26 is supplied through manifold 24 to heat exchanger 10 where it is heated in passageway 12 by means of end position heaters 28 and 30. The heated air then passes into jet 82 for yarn bulking purposes.

With reference to FIGURE 3, there is shown a block diagram illustrating how the novel apparatus of this invention is utilized commercially. A plurality of heat exchangers are serially connected to a single recorder controller. In practice, up to about 24 heat exchangers can be used to accommodate the yarn from a conventional drawtweaver. As illustrated each heat exchanger 10 has a precision variable resistor 80 which is connected in the line between thermocouple 74 and recorder controller 72.

In operation, thermocouple 74 measures the temperature of heat exchanger 10 and sends a signal to recorder controller 72. Whenever the temperature falls below a designated set point, the recorder controller through conventional relay circuitry (not shown) closes contacts C1 and C2 thereby energizing swing load heaters 30, 34, 38, 40, 44 and 48. As hereinbefore mentioned, base load heaters 28, 32, 36, 42, 46 and 50 remain on at all times. After the temperature exceeds the set point, the controller

turns off the swing load heaters by opening contacts C1 and C2. In this manner the temperature measured by the thermocouple is closely maintained at a given point. End position heaters 28, 30, 48 and 50 are connected to variable transformer 56 which supplies a predetermined higher voltage to these positions, thereby providing higher heat input to compensate for the heat losses at end positions 12 and 22 and thus reducing the differential in dye depth of the bulked yarn between the various positions of each heat exchanger from 10.3% to 2.5% as shown in the experimental data of Table I. The yarn tested was a 105 denier nylon yarn.

TABLE I

End Pos. (28, 30, 48, 50), Voltage	Intermediate Pos. 32 through 46, Voltage	Percent Yarn Dyeability			Total Variation Percent
		End Pos. 12, 22	2nd Pos. 14, 20	Middle Pos. 16, 18	
78	96	95.9	104.6	98.6	8.7
96	96	103.9	106.7	114.2	10.3
115	96	108.6	110.5	108.0	2.5

In addition, a variation in temperature among the heat exchangers on a bulking machine can exist because of small differences in fit and positioning of thermocouple 74. To insure that the dyeability of the bulked yarn from each heat exchanger is similar to that from every other heat exchanger these temperature differences are minimized by installing a precision variable resistor 80 in the thermocouple circuit for each heat exchanger. The thermocouples 74 are individually calibrated by adjusting their resistors 80 and in this manner the temperature at which the recorder controller 72 will operate is predetermined for each heat exchanger.

With respect to the preferred embodiment, it is preferred that the compressible fluid be compressed air and that the heat exchanger be made of copper. However, the fluid may also be steam or any other vapor capable of exerting a plasticizing action on the material of the yarn. Similarly, the heat exchanger may be made of any conductive metal, alloy or substance which can accommodate heaters that must heat the compressible fluid to a temperature such that the temperature of the yarn to be bulked is in the range of the melting point of the yarn.

Referring to other elements utilized in the novel apparatus of this invention, many different types of elements can be used. For example, the recorder controller can be of any conventional design. The relay circuitry can similarly embody any conventional design, such as an air solenoid.

Although Table I illustrated the effects of the use of this invention on a nylon yarn, it should be obvious that the use is not so restricted. The novel apparatus of this invention can be advantageously utilized to heat compressible fluids to, in turn, heat any yarn of a thermoplastic material which is to be bulked in a process such as is disclosed in British Patent No. 905,895. For example, the thermoplastic material may be polyamides, e.g., poly-(ϵ -caproamide) and poly(hexamethylene adipamide); polyesters, e.g., terephthalate esters of ethylene glycol and of trans- ρ -hexahydroxyethylene glycol; polyalkylenes, e.g., polyethylene and polypropylene; polyvinyls and polyacrylics, e.g., polyacrylonitrile, as well as copolymers thereof.

15 Since many different embodiments may be made without departing from the spirit and scope of this invention, it is understood that the invention is not limited to this specific illustration except as defined in the appended claim.

20 What is claimed is:

An apparatus for heating compressible fluids used to bulk yarn which comprises a heat exchanger having a plurality of separate co-planar passageways therethrough, means to supply compressible fluids to each of said passageways, a swing load heater on one side and a base load heater on the other side of each of said passageways, voltage source means connected to each intermediate heater, first switch means connected between said voltage source means and the intermediate swing load heaters, transforming means connected to the said voltage source means to supply the end position swing load and base load heaters with a predetermined voltage greater in magnitude than the voltage supplied by said voltage source means, second switch means connected between said transforming means and the end position swing load heaters, measuring means responsive to the temperature of said heat exchanger and control means responsive to the output of said measuring means to close said first and second switch means when the output of said measuring means falls below a predetermined point and to open said first and second switch means when the output exceeds the predetermined point.
